UNITED STATES PATENT OFFICE.

WILMA SANDA, OF NEW YORK, N. Y.

DESIGN FOR SKIRT-TRousERS.

52,245.

Specification for Design. Patented July 30, 1918.

Application filed February 18, 1918. Serial No. 218,009. Term of patent 14 years.

To all whom it may concern:

Be it known that I, WILMA SANDA, a citizen of the United States, and a resident of the city of New York, borough of Manhattan, in the county and State of New York, have invented a new, original, and ornamental Design for Skirt-Trousers, of which the following is a specification, reference being had to the accompanying drawing, forming a part thereof.

The figure is a perspective view of the skirt trousers showing my new design.

I claim:

The ornamental design for skirt trousers as shown.

WILMA SANDA.
